TOBACCO ARTICLE MAKING MACHINE

Sigurd Clausen, Brooklyn, N. Y., assignor to International Cigar Machinery Company, a corporation of New Jersey

Application August 30, 1934, Serial No. 742,179
Renewed February 1, 1936

21 Claims. (Cl. 131—14)

This invention relates to a tobacco bunch making machine suitable for the manufacture of chewing or smoking bunches. It has been proposed to make these articles by forming a rod or roll of tobacco and then cutting the same into a number of bunches simultaneously, but it has been found that this tends to crush the tobacco rod. Accordingly, the main object of this invention is to avoid the described disadvantage of prior machines by producing a machine having a novel combination of elements and a novel mode of operation.

In pursuance of the same there is provided a machine which resembles a Toscani cigar machine, except that paste is applied only along one edge of the wrapper instead of over the entire wrapper, and after the wrapper is applied to the filler charge the tobacco rod or roll so formed is trimmed to a predetermined length and transferred to a channel wherein it is intermittently advanced endwise between opposed cutters and thereby cut into bunches of the desired length. The tobacco rod is advanced endwise in the channel by a pusher or plunger having an intermittent movement equal to the desired length of bunch, and at the end of each feeding movement of the plunger the opposed cutters sever a bunch from the tobacco rod, the severed bunches being then collected and wrapped.

With this and other objects not specifically mentioned in view, the invention consists in certain constructions and combinations hereinafter fully described and then specifically set forth in the claims hereunto appended.

In the accompanying drawings which form a part of this specification and in which like characters of reference indicate the same or like parts:

Fig. 1 is a partial side elevation of the bunch making machine;

Fig. 2 is a sectional detail view, taken on line 2—2 of Fig. 1, of the pawl and ratchet mechanism for driving the feed belts;

Fig. 3 is a partial top elevation showing the feed belt drive;

Fig. 4 is an end view of the eccentric drive for the feed belts;

Fig. 5 is a side view of the same;

Fig. 6 is an end view showing the rod-trimming and bunch-cutting mechanism;

Fig. 7 is a side view of the same;

Fig. 8 is a detail view showing the mounting of the trimmer knives;

Fig. 9 is a partial side view illustrating the holding means of the trimmers;

Fig. 10 is an end view showing the adjusting means provided for the rolling apron;

Fig. 11 is a side view showing the ends of the cigar being trimmed; and

Figs. 12, 13 and 14 show the tobacco rod being advanced and cut into bunches.

In carrying the invention into effect there is provided means for forming a tobacco rod, mechanism for trimming the rod to predetermined length, means for advancing the trimmed rod 10 endwise, and a device for cutting the trimmed rod into bunches in said rod-advancing means. In the best constructions contemplated the rod forming means includes a plurality of belts arranged to form a channel, mechanism for intermittently driving the belts to intermittently advance a continuous stream of tobacco in the channel, a rod-rolling device, mechanism for severing a charge from the stream and depositing the severed charge on a pasted wrapper on said device, and a device controlled by the charge-severing mechanism for compressing the stream of tobacco in the channel while the charge is being severed. With the best constructions the rod-trimming mechanism includes a pair of stationary ledger plates, a pair of spaced trimmer knives opposed to the ledger plates, and means for actuating the trimmer knives to propel the tobacco rod sidewise past the ledger plates to trim the ends of the rod and deliver the trimmed rod to 20 the rod-advancing means; the rod-advancing means operates to move the rod endwise step-by-step and the bunch-cutting device includes a pair of opposed knives for severing the rod while it is at rest.

These various means and parts may be widely varied in construction within the scope of the claims for the particular machine selected to illustrate the invention is but one of many possible concrete embodiments of the same. The 40 invention, therefore, is not to be restricted to the specific construction shown and described.

Referring to Fig. 1 of the drawings, the bed 20 is supported by the end frames 21, the former carrying brackets (not shown) which support 45 the base 22.

The scrap tobacco is fed from a hopper (not shown) and falls into the channel formed by a horizontal endless bottom belt 23, and the vertical endless side belts 24 and 25. The bottom 50 belt 23 runs over drive pulleys 26 and 27, and over idler pulleys 28 and 29, the pulleys 26 and 27 being mounted in pedestal 30 and the pulleys 28 and 29 being supported in bracket 31. The side belts 24 and 25 run over drive pulleys 32 and 33 55

mounted on base 22, and over idler pulleys 34 and 35 (Fig. 3) also mounted on base 22. The bottom belt and side belts at the end of the channel underlying the hopper run over other 5 idler pulleys, not shown. The tobacco is advanced in the form of a continuous stream by the feed belts, and the upper run of the belt 23 on which the tobacco is advanced is supported by the bottom plate 36.

10 On entering the filler cutoff the mass of tobacco is cut into charge lengths, the filler cutoff being mounted on the base 22 and consisting of a vertical slide 37, an operating lever 38 connected to the slide 37 by means of a link 39, and the 15 stationary ledger plate 40 fastened to brackets 41 and 47 attached to the base 22. The base 22 is provided with upright slideways 42 for the knife slide 37 carrying the cutter blade 43, and a lug 44 supporting the shaft 45 on which the operating 20 lever 38 is fulcrumed. The lever 38 is actuated by an adjustable pitman 46 one end of which is connected to lever 38 and the other end of which is connected to a cam lever 189 fulcrumed on a shaft 190 and having a cam follower 191 in engagement with a cam 192 on cam shaft 193 of the 25 machine.

Attached to the slideways 42 are the long bracket 41 and a short bracket 47 on which the ledger plate 40 is supported and the trap doors 30 48 are pivoted, the latter being normally held in a horizontal position in which they form a continuation of the belt 23, by tension springs 50. The slide 37 carries an adjustable plate 49 which engages with and opens the doors 48 as the knife 35 descends, thus delivering the cut charge into the chianti belt or the rolling apron of the cigar forming mechanism, the torsion springs 50 closing the doors 48 as the knife ascends and lifts the plate 49.

40 To a cam shaft 51 (Figs. 4 and 5) is fastened an eccentric 52 revoluble in eccentric straps 53 and 54. The strap 54 is provided with a boss 55 receiving one end of an eccentric rod 56, the other end thereof being fastened to a head 57 pivoted 45 on a stud 58 carried by an arm 59. A gear 60 fastened to shaft 51 is driven from the main drive of the machine by means of chain 194 running over sprocket 195 fixed to shaft 51 and sprocket 196 fastened to the main shaft 193 of the 50 machine. The rotation of the eccentric 52 actuates, through the rod 56 the arm 59 which is pivotally mounted on a shaft 61. The slotted end of arm 59 receives a stud 62 on one end of a rod 63, the other end of rod 63 being connected to arm 64 55 integral with a gear segment 66 fastened on a shaft 65 supported in the pedestal 30 (Fig. 1). The gear segment 66 meshes with a gear 67 loosely mounted on shaft 68. An arm 69 is keyed to the hub of gear 67, the arm 69 carrying a stud 60 70 on which is mounted a pawl 71 engaging with a ratchet 72 keyed to shaft 68, and a spring 72a stretched between a spring post in the pawl and a post anchored in the arm 69 holds the pawl 65 in engagement with the ratchet. A sprocket 73 fast on the shaft 68 (Fig. 2) drives a chain 74 running over idlers 75 and 76 and over a sprocket 77 mounted on a shaft 78 supported in bearings 79 of the base 22.

When the rod 63 ascends the segment 66 70 through the pawl and ratchet arrangement drives the shaft 68 and all the members mounted on the same. Upon the downstroke of the rod 63 the pawl 71 slips over the teeth of the ratchet, whereupon the gear 67 turns freely on the then stationary shaft 68.

Referring now to Fig. 3, a pair of bevel gears 80 and 81 fast to shaft 78 mesh with a pair of gears 82 and 83 respectively, the latter being mounted on the vertical shafts 84 and 85 which drive the side belt pulleys 82 and 83. The shaft 68 carries a gear 86 which meshes with a gear 87 mounted on a shaft 88, whereby the bottom belt pulleys 26 and 27 are driven in union to intermittently advance the stream of tobacco on the bottom belt 23. A bracket 89 attached to the bracket 30 supports the shaft 68.

During the descent of the rod 63 (Fig. 1) the drive of the belts 23, 24 and 25 is stopped; at this time the operating lever 38 descends and, through the links 39, causes the slide 37 to bring the knife 15 43 into cutting engagement with the mass of tobacco on the trap-doors 50 and sever a charge therefrom along the ledger plate 40. A lug 90 on lever 38 engages a roller 91 carried by an arm 92. The arm 92 is pivoted on a stud 93 carried 20 by a bracket 94 fastened to the slideway 42. On the free end of arm 92 is carried a forked head 95 supporting a rod 96 connected to a slide rod 97 guided in the brackets 98 on base 22. The lower end of rod 97 is fastened in a frame 99 which 25 carries the compressor plate 100. A tension spring 101 stretched between head 95 and bracket 98 tends to depress the slide rod 97 and bring the compressor plate 100 into engagement with the mass of tobacco on the belt 23. While the compressor 100 remains in contact with the charge the continued descent of the slide 37 causes the knife 43 to cut the charge. The then cut charge drops from its position on the trap-doors 48 (Fig. 10) when the plate 49 encounters 35 and swings open said doors, and the slide 37 presses the charge down on a pasted wrapper on the section of the chianti belt 102 overhanging the forming table 127, the continued downward movement of the slide forming a loop 102' in 40 the apron 102, as indicated by dotted lines in Fig. 10. The wrapper may be transferred to the chianti belt from a cutting bed (not shown) by a wrapper carrier of well known construction of the type shown in Patent No. 1,543,874 granted 45 to R. E. Rundell, June 20, 1925, or may be placed thereon manually, and pasted by a paster of the type shown in Patent No. 1,945,037, granted January 30, 1934, on the application of J. F. Halstead.

After the charge is thus located in the loop of 50 the chianti belt the slide 37 ascends and in so doing permits the springs 50 to close the trap doors 48 in readiness to receive the next charge. The compressor 100 retains its position during the ascent of the slide and acts as a stripper 55 on the stream of tobacco on belt 23 until the cutting edge of knife 43 has passed the base 99 of the compressor; at this point the lug 93 of arm 38 engages the roller 91, thereby lifting the arm 92 until the compressor 100 is clear of the tobacco 60 on belt 23 as the continued ascent of the slide returns the knife and the compressor to their original positions.

To the shaft 51 (Fig. 10) are attached the face cams 103 and 104 having cam tracks in which 65 engage the cam rollers 105 and 106 of cam levers 107 and 115 respectively. The cam lever 107 is fulcrumed on a stud 108 in the bracket 109 which is attached to the bed 20. In the upper end of lever 107 is fixed a stud 110 on which is pivotally 70 mounted a U-shaped apron tightener arm 111 (Figs. 1 and 10). The arm 111 is provided with an adjusting screw 112 bearing against a lug 113 of the lever 107. The adjusting screw 112 is conveniently located and provides means for swing- 75

ing the arm 111 in or out, for loosening or tightening the rolling apron 102. A torsion spring 114 placed on the stud 110, and having its ends anchored to the stud and apron-tightener arm, assures constant engagement of the adjusting screw with the lug. 5

The cam lever 115 is fulcrumed on shaft 61 and its upper end is provided with a head 116 carrying an adjustable pitman 117 connected to a carriage 118 equipped with studs 119 supporting flanged rollers 120 which travel between the tracks 121 and 122, the same being fastened to brackets 123 (Fig. 1). In the boss 124 of stud 125 carried by this carriage 118, is journaled one end of the forming roller 126 which is journaled at its other end in the same manner in a carriage 118 similarly mounted to travel on another set of tracks 121 and 122. One end of the chianti belt 102 (Fig. 10) is fastened to the far end of the forming table 127 and passes over the forming roller 126 and over a tightener pin 128 carried by the arm 111, its other end being clamped to a bracket 129 fastened to the bed 20.

While the slide 37 presses the charge down 25 into the chianti belt 102 to form the loop 102', therein, the forming roller is at its dotted position 126', and the arm 111 which is in its "out" position (not shown), moves inwardly sufficiently to loosen enough of the chianti belt to allow the 30 slide 37 to form the loop 102' and compress the charge therein. The slide 37 then ascends and the forming roller moves across the forming table 127 from its dotted position 126' and starts to roll the charge in a binder which has been previously deposited on the chianti belt, thus forming 35 a shaped tobacco roll or rod, the arm 111 simultaneously moving back to take up the slack in the chianti belt. At the completion of its stroke the forming roller reaches a position beyond the end of the table 127, whereupon the shaped tobacco rod falls onto a bridge 130 (Fig. 6) located between the trimmer knives 131 and 131a.

The shaft 51 (Figs. 6 and 7) carries the cams 40 132, 133 and 134. In the cam groove of face cam 132 is fitted a cam roller 135 of a cam lever 136 fulcrumed on the shaft 61. The upper end of lever 136 carries a link 137 connected to an arm 138 clamped to the shaft 139 which is supported in the bearings 140 and 141 attached to the bed 20 (Fig. 8). A pair of spaced arms 142 splined on shaft 139 each carry a trimmer or knife 131; the shaft 139 is being turned through its connections with the cam lever 136 causing the knives 131 to push the cigar sidewise against the stationary knives or ledger plates 131a whereby the ends of the tobacco rod are trimmed to obtain a rod having a predetermined length. The knives 131 continue to propel the now 45 trimmed rod along the bridge 130, and deposit the same in the channel 143 of bridge 130, whereupon the trimmer knives return to their starting position.

The plate cam 133 engages the roller 144 on the cam lever 145 pivoted on a stub shaft 146 supported in a bracket 147 suspended from the bed 20. The free end of lever 145 carries a ball pin 148 fitted into a socket 149 connected by means of an adjustable rod 150 to a socket 151 receiving a ball pin 152 carried by an arm 153 of bell crank lever 154. The movement of lever 154 actuates an arm 155 pivoted to a stud 156 in lever 154, a roller 157 on arm 155 being thereby moved under the cam rail 158 attached to a clamp finger 159 to raise and lower the latter. The finger

159 is mounted on a block 160 pivotally mounted on a stud 161 carried by bracket 162. The bracket 162 is equipped with a lug 163 which serves as an abutment for the adjustable stop screw 164 of finger 159 which secures it in proper 5 adjusted position with respect to the rod beneath it. The free end of arm 155 supports a pusher 165 which rests in the channel 143 and serves to move the tobacco rod axially in the channel while the finger 159 retains it therein. 10 The lever 154 is fulcrumed on a stud 166 carried by the bracket 167 which is suspended from the bed 20.

The bunch cutter cam 134 engages a roller 168 on cam lever 169 fulcrumed on the stub shaft 15 166 in bracket 147. The lever 169 actuates a pitman 170 connected to a bell crank 171 which is pivoted on stud 172 in a forked bracket 173 clamped to a stud 174 carried in bracket 147. On stud 175 carried by the forked ends of bracket 20 173 are pivoted the knife holders 176 and 177 carrying the bunch-cutting knives 178 and 179 respectively. Each knife holder 176, 177 has a slotted arm 180 and 181, respectively, engaging with the pin 182 in the bell crank 171. 25

When the rod 170 is pulled downwards by the cam lever 169, the bell crank 171 with its pin 182 turns on the stud 172, thereby depressing arm 180 and raising arm 181 and thus operating the bunch-cutting knives 178 and 179 to sever a butt 30 from the tobacco roll in the channel 143.

Referring to Figs. 8 and 9, the arms 142 are splined on shaft 139, each arm 142 carrying a bolt passing through a slot in the adjacent ledger plate 131a and equipped with a compression spring 184 tending to press the knives 131 laterally against the ledger plates 131a. The ledger plates 131a are carried on a clamp rod 185 held by clips 186 fastened to the bed 20, said arrangement holding the knives 131a stationary. 40

The tobacco roll or rod C is discharged from the rolling apron 102 (Fig. 6) onto the bridge 130 while the trimmer knives 131 are in their open position. The movable trimmer knives 131 are then actuated to propel the tobacco rod past 45 the ledger plates 131a, thereby trimming the ends of the same to its desired length. The knives 131 continue to propel the trimmed rod until the same rests in the channel 143 of bridge 130, whereupon the knives 131 retreat while the 50 pusher 165 is actuated by the lever 154 operated from cam 133, thereby permitting the clamp finger 159 to descend and rest on the tobacco rod and hold it in the channel while it is being cut into bunches, and advancing the tobacco rod 55 endwise between the bunch cutter knives 178 and 179 when the latter are in their open position.

By means hereinbefore described the bunch cutters are then actuated to cut the protruding end of the cigar, the bunch thus cut falling into 60 a chute 187 (Fig. 7) carried by the bed 20. The severed bunch passes through the chute 187 onto a deflector plate, not shown, which guides the same to a storage receptacle. The remaining portion of the tobacco rod is similarly advanced 65 step-by-step and cut into bunches as illustrated in Figs. 12, 13 and 14.

What is claimed is:

1. In a tobacco bunch making machine, the combination with means for forming a tobacco 70 rod, of mechanism for trimming the rod to predetermined length, means for advancing the trimmed rod endwise, and a device for cutting the trimmed rod into bunches while it is engaged by said rod-advancing means. 75

2. In a tobacco bunch making machine, the combination with means for forming a tobacco rod, of mechanism for trimming the rod to predetermined length, a rod support, means for advancing the trimmed rod endwise along said support, and a device for cutting the trimmed rod into bunches while it is on said support, said rod forming means including a plurality of belts arranged to form a channel, mechanism for intermittently driving said belts to intermittently advance a continuous stream of tobacco in said channel, a rod-rolling device, mechanism for severing a charge from said stream and depositing the severed charge on a pasted wrapper on said device, and a device controlled by said charge-severing mechanism for compressing the stream of tobacco in said channel while a charge is being severed.
3. In a tobacco bunch making machine, the combination with means for forming a tobacco rod, of mechanism for trimming the rod to predetermined length, means for advancing the trimmed rod endwise, and a device for cutting the trimmed rod into bunches while it is engaged by said rod-advancing means, a channeled bridge, said rod-advancing means including a pusher arranged to advance a trimmed rod endwise in the channel of said bridge, and means for imparting a step-by-step movement to said pusher to advance the rod in said channel step-by-step.
4. In a tobacco bunch making machine, the combination with means for forming a tobacco rod, of mechanism for trimming the rod to predetermined length, means for advancing the trimmed rod endwise, and a device for cutting the trimmed rod into bunches while an end thereof is in contact with said rod-advancing means, said rod-advancing means operating to move the rod step-by-step, and said device including a pair of opposed knives, and means for actuating said knives to sever the rod while it is at rest.
5. The combination with a plurality of belts arranged to form a channel, of mechanism for intermittently driving said belts to intermittently advance a continuous stream of filler tobacco in said channel, a rod-rolling device, mechanism for severing a charge from said stream and depositing the severed charge on a pasted binder on said device, a device controlled by said charge-severing mechanism for compressing the stream of tobacco in said channel while a charge is being severed, and means for cutting the rolled rod into bunches by successive cutting operations.
6. The combination with mechanism for trimming a tobacco rod to predetermined length, of means for advancing the trimmed rod endwise, and a device for cutting the trimmed rod into bunches during its engagement with said rod-advancing means.
7. The combination with mechanism for trimming a tobacco rod to predetermined length, of means for advancing the trimmed rod endwise, and a device for cutting the trimmed rod into bunches during its engagement with said rod-advancing means, said rod-trimming mechanism including a pair of spaced stationary ledger plates, a pair of spaced trimmer knives opposed to said ledger plates, and means for actuating said knives to propel a tobacco rod sidewise against said ledger plates and thus trim the ends of the tobacco rod along the ledger plates, and delivered the trimmed rod to said rod-advancing means.
8. The combination with mechanism for trimming a tobacco rod to predetermined length, of means for advancing the trimmed rod endwise, and a device for cutting the trimmed rod into lengths during its engagement with said rod-advancing means including a channeled bridge, said rod-advancing means including a pusher arranged to advance a trimmed rod endwise in the channel of said bridge, and means for imparting a step-by-step movement to said pusher to advance the rod in said channel step-by-step.
9. The combination with mechanism for trimming a tobacco rod to predetermined length, of means for advancing the trimmed rod endwise, and a device for cutting the trimmed rod into lengths during its engagement with said rod-advancing means, said rod-advancing means operating to move the rod step-by-step, and said device including a pair of opposed knives and means for actuating said knives to sever the rod while it is at rest.
10. The combination with mechanism for trimming a tobacco rod to predetermined length, of means for advancing the trimmed rod endwise, a device for cutting the trimmed rod into bunches during its engagement with said rod-advancing means, and means for holding the rod while it is being cut.
11. The combination with mechanism for trimming a tobacco rod to predetermined length, of means for moving said trimmed rod axially, and a device for dividing the trimmed rod into a plurality of lengths.
12. In a tobacco bunch making machine, the combination with means for forming a tobacco rod, of mechanism for trimming said rod to a predetermined length, means for moving said trimmed rod endwise, and means for dividing said rod into a plurality of lengths.
13. In a tobacco bunch making machine, means for rolling a charge of tobacco and a binder into a tobacco rod, means for moving the rod sideways onto a support, a device for moving said rod endwise while on said support, and means for progressively cutting said rod into a plurality of bunches.
14. In a bunch making machine, means for forming a tobacco rod, means for trimming the rod to a predetermined length and transferring the rod to a support, a device for moving said trimmed rod endwise on said support and means for progressively cutting the rod into a plurality of butts.
15. In a bunch making machine, means for forming a tobacco rod, means for trimming the rod to predetermined length and moving it sideways onto a support, means for intermittently moving the trimmed rod endwise on the support, and means for successively cutting said rod during dwells in its motion into a plurality of lengths.
16. The combination with mechanism for trimming a tobacco rod to predetermined length, of means for advancing the trimmed rod endwise, a device for cutting the trimmed rod into lengths, and an adjusting device for the advancing means for controlling the size of the lengths cut.
17. In a bunch forming machine, the combination with a rod rolling device, of mechanism for feeding filler tobacco, means for separating a charge from said fed tobacco and depositing it upon a binder on said device, means for transferring the rolled rod from said device, and means for cutting the rod by successive cuts into a plurality of bunches.
18. In a bunch forming machine, means for feeding filler tobacco, means for separating a charge from the fed tobacco and depositing it

- upon a binder, a rod rolling device for supporting said binder and rolling said binder and charge into a rod, means for trimming the rod to a pre-determined length and transferring it onto a support, means for moving said rod step by step along said support, and means acting on the rod while on said support for successively cutting said rod between moving steps into a plurality of bunches.
10. 19. The combination with a plurality of belts arranged to form a channel, of mechanism for intermittently driving said belts to intermittently advance a continuous stream of filler tobacco in said channel, a rod rolling device, including a rolling apron, mechanism for severing a charge from the stream and depositing the severed charge on a pasted binder on said device, a device controlled by said charge severing mechanism for compressing the stream of tobacco in said channel while a charge is being severed, a rod
15. cutter, and means for producing relative axial movement between said rod and cutter to cut said rod into a plurality of bunches.
20. 20. In a bunch forming machine, the combination with a rod rolling device, of mechanism for feeding filler tobacco, means for separating a charge from said tobacco and depositing it upon a binder on said device, means for transferring the rolled rod from said device, a cutter, and means for producing relative axial movement between said rod and cutter to divide the rod into a plurality of bunches.
21. 15. In a cigar bunch machine, mechanism for trimming and cutting a tobacco rod into a plurality of bunches, comprising a cutter device, and means 10 for producing relative axial movement between said rod and device to divide said rod into said bunches.

SIGURD CLAUSEN.

20
